UNITED STATES PATENT OFFICE.

WILLIAM J. HUTCHINSON AND THOMAS A. MITCHELL, OF WASHINGTON, DISTRICT OF COLUMBIA, ASSIGNEES OF TWO-THIRDS TO JAMES A. BEALMEAR, OF BALTIMORE, MARYLAND.

BOLT-LOCK FOR RAILROAD-JOINTS.

SPECIFICATION forming part of Letters Patent No. 428,560, dated March 18, 1890.

Application filed June 14, 1889. Serial No. 314,240. (No model.)

To all whom it may concern:

Be it known that we, WILLIAM J. HUTCHINSON and THOMAS A. MITCHELL, citizens of the United States, residing at Washington, in the District of Columbia, have invented certain new and useful Improvements in Bolt-locks for Railway-Joints; and we do hereby declare the following to be a full, clear, and exact description of the invention, such as will enable others skilled in the art to which it appertains to make and use the same, reference being had to the accompanying drawings, which form part of this specification.

Our invention relates to certain improvements in bolt-locks for railway-joints of that construction in which a series of bolts are made to project through the fish-plates, and has for its object to provide a secure and substantial lock for the bolts, that will not be affected by the jarring of the rails and constant vibration of the track, which frequently loosens and releases screw-threaded and many other forms of locks now in use, enabling the bolts to gradually withdraw from the fish-plates and rails and the joints to become disconnected, resulting in serious accident by throwing the train from the track; and it consists in the construction hereinafter described, and more particularly pointed out in the claim.

Referring to the drawings, Figure 1 is a perspective view of two sections of the rail secured together in the ordinary way with fish-plates and bolts with our invention applied thereto. Fig. 2 is a cross-section through the rail on the line α α of Fig. 1, showing our improved keys and locking-pin inserted in the keys. Fig. 3 is a perspective view of two of the bolts removed from the rail and having our improved keys inserted therein and locked. Fig. 4 is a side view of the fish-plate with bolts therein, having a slightly-modified form of our key and lock therein. Fig. 5 is a side view of the key shown in Fig. 4. Fig. 6 is a perspective view of our modified form of locking-pin shown in Fig. 4. Fig. 7 is a plan view of the locking-pin shown in Fig. 3 before

insertion; and Fig. 8 is a section of the bolt, showing the slot having an inclined outer end.

Like letters refer to corresponding parts in each figure of the drawings.

A represents the ordinary railway-rails, having their ends abutting, and B the fish-plates embedded in the groove on each side thereof formed by the main tread a and the flange b of the base of the rail, holding the two ends in contact. The fish-plates are secured to the rail by means of two or more bolts C on each side of the joint through the vertical center of the rail and the fish-plates, which extend over the sides of the ends of the rails. The bolts C are provided with longitudinal slots c near their outer ends. These slots are slightly inclined or wedge-shaped at their outer ends, and the sides of the bolt having the shortest external slots are turned toward each other after the bolts are passed through the fish-plates. Within the slots c we insert keys D, which are of malleable or other suitable iron, made of a uniform thickness, having their outer edges slightly tapering from one end to the other to form a wedge-shaped key. The small or inner ends d of the keys are beveled to a chisel edge, so that when the beveled edges are turned from each other and the keys are inserted in the slots of the bolts from opposite directions the ends will slide one over the other without being obstructed by coming in contact.

Near the small ends of the key D there is a series of openings E through the key that are made to register with a like series of holes in the key driven in the slot of the bolt from the opposite direction. The bolts are of a uniform distance apart in the rails and fish-plates, and as the wedge-shaped keys are driven through their slots their inner ends slide one over the other until the limited distance through the slots is reached, when the holes E register in the separate keys. A pin F, made of single pieces of wire, having a loop-head f , with two projecting parallel prongs e , is inserted through the registering openings of the keys, and the prongs are bent

in opposite directions, thereby securely locking them together as against any separation from a jarring or vibrating motion of the trains. The keys D may be left loose in the 5 slots of the bolts, if desired, by placing the pin F in the registering holes before the keys are driven into the slots of the bolts; or they may be drawn more closely together and secured after they have become worn or loosened by rust. As the wire pins F are sometimes broken by bending in releasing and again securing the ends of the keys, the pins may be made of sheet metal, if desired, with a modified form of opening in the keys, as 10 shown in Figs. 4, 5, and 6. In this instance the openings E in the keys are made rectangular in form, and the pins F are cut or stamped out of sheet metal or steel, with the head portion wider than the prongs. The 15 blank for the pin is then bent in the center, forming a substantially circular head f, with the prongs e extending parallel to each other and side by side until near their ends, when they are bent outward in opposite directions, 20 and then inward to near a meeting-point. The outer bent portions of the prongs of this construction of pin, when inserted in the registering rectangular openings in the keys, are crowded together, and after they have passed 25 through the openings they spring outward, locking the pin in place and the keys securely together.

In stamping out or otherwise forming the holes in the rails for the reception of the 30 bolts C the holes are made of an elongated

form to compensate for the variations in temperature which contract and expand the metal.

As shown in both forms of our invention, the wedge-shaped keys through the inclined 40 slots of the bolts are securely locked by the pins as against all accidental separation and removal.

We are aware that it is not new to insert a wedge-shaped key in the slot of a bolt, and 45 such we do not claim, broadly; but,

Having thus fully described our invention, what we claim as new, and desire to secure by Letters Patent of the United States, is—

The combination, with fish-plates and bolts 50 having slots near their ends inclined at the outer edge, of keys having a uniform thickness and one edge tapering from end to end, forming a wedge, the inner or narrowest ends having a chisel edge and a series of openings 55 near the ends, the keys inserted through the slots from opposite directions, and the openings in the keys registering with each other, the keys being secured together by a pin through the openings, having its arms bent in 60 opposite directions against the key, as set forth.

In testimony whereof we affix our signatures in presence of two witnesses.

WM. J. HUTCHINSON.
THOMAS A. MITCHELL.
